(57) **CLAIM**

The ornamental design of a massage roller as shown and described.

DESCRIPTION

FIG. 1 is a top and first multi-side isometric view of a massage roller showing our new design.

FIG. 2 is a top and second multi-side isometric view of the massage roller of the present design, with a top cap portion shown in phantom thereof.

FIG. 3 is a top and third multi-side isometric view of the massage roller of the present design, with a top cap portion shown in phantom thereof.

FIG. 4 is first side elevation of the massage roller of the present design, and with a top cap portion shown in phantom view thereof.

FIG. 5 is a second side elevation view of the massage roller of the present design, including portions of the elements shown in FIG. 4, and with a top cap portion shown in phantom thereof.

FIG. 6 is a third side elevation view of the massage roller of the present design, including portions of the elements shown in FIGS. 4 and 5, and with a top cap portion shown in phantom thereof.

FIG. 7 is a fourth side elevation view of the massage roller of the present design, including portions of the elements shown in FIGS. 5 and 6, and with a top cap portion shown in phantom thereof.

FIG. 8 is a fifth side elevation view of the massage roller of the present design, including portions of the elements shown in FIGS. 6 and 7, and with a top cap portion shown in phantom thereof.

FIG. 9 is a sixth side elevation view of the massage roller of the present design, including portions of the elements shown in FIGS. 7 and 8, and with a top cap portion shown in phantom thereof.

FIG. 10 is a seventh side elevation view of the massage roller of the present design, including portions of the elements shown in FIGS. 8 and 4, and with a top cap portion shown in phantom thereof.

(Continued)

FIG. 11 is an eight side elevation view of the massage roller of the present design, including portions of the elements shown in FIGS. 10 and 4, and with a top cap portion shown in phantom thereof.

FIG. 12 is a top cap an enlarged top plan view of the massaging roller of the present design, with a top cap portion shown in phantom thereof; and,

FIG. 13 is an enlarged bottom plan view thereof.

The broken lines showing a top cap portion and the bottom surface are for illustrating portions of the massage roller and form no part of the claimed design.
